(57) **CLAIM**

The ornamental design for a steering wheel, as shown and described.

DESCRIPTION

1. Steering wheel

1.1 : Perspective

1.2 : Front

1.3 : Back

1.4 : Left

1.5 : Right

1.6 : Top

1.7 : Bottom

1.8 : Perspective

1.9 : Front

1.10 : Back

1.11 : Left

1.12 : Right

1.13 : Top

1.14 : Bottom

Reproduction 1.1 to 1.7 show the claimed design in the first position and reproduction 1.8 to 1.14 show the claimed design in the second position.

1 Claim, 14 Drawing Sheets
